WEATHER STRIP FOR DOORS AND THE
LIKE

Thomas Monroe Hester, Hawthorne, Calif.

Application September 25, 1941, Serial No. 412,313

1 Claim. (Cl. 20—67)

My invention relates to improvements in weatherstrips for doors, windows, and other openings, the principal object in view being to provide a device of this character which will positively prevent dust, snow, rain, and wind from seeping in around the edges of doors, or window sashes, and which is easy to apply, strong and durable, inexpensive to manufacture and install, and will not interfere with opening the door or window as the case may be.

Other and subordinate objects are also comprehended by my invention, all of which, together with the precise nature of my improvement, will be readily understood when the succeeding description and claim are read with reference to the drawings accompanying and forming part of this specification.

In said drawings:

Figure 1 is a view in front elevation illustrating a preferred embodiment of my invention.

Figure 2 is a view in vertical section taken on the line 2—2 of Figure 1.

Figure 3 is a fragmentary view in front elevation illustrating the hinge drawn to an enlarged scale,

Figure 4 is a view in section taken on the line 4—4 of Figure 3.

Figure 5 is a view in front elevation of a modified adaptation of my invention.

Figure 6 is a view in vertical section taken on the line 6—6 of Figure 5 and drawn to an enlarged scale, and

Figure 7 is a view in transverse section taken on the line 7—7 of Figure 5 and drawn to an enlarged scale.

Referring to the drawings by numerals, and first to Figures 1, 2, 3 and 4, according to a preferred purpose of my invention, top, bottom and side weatherstrips 1, 2 and 3, respectively, of rectangular form in cross-section and having a felt covering 4 on all four sides thereof are applied to the outer face of the usual swinging door 5 to extend along the top, bottom and side edges thereof, respectively, and fit flush against the top, bottom and side members 6, 7 and 8 of the door frame 9. The strips 1, 2, 3 may be of any desired size, transversely, and formed of wood, metal, or any other suitable material. Preferably the side strips 3 extend from top to bottom of the door 5 and the top and bottom strips 1, 2 fit lengthwise in between the side strips 3 flush against the same.

Each strip 1, 2, 3 is secured to the door 5 by a plurality of hinges each of which comprises a fixed plate 10 secured to the door 5 by screws 11,

and a longer movable plate 12 curving from the pintle 13 of the hinge over the outer side of the strips 1, 2, 3, as the case may be, to which side it is secured flat at its outer end as by screws 14.

5 A coil spring 15 is suitably arranged around the pintle 13 of each of said hinges to urge the movable plate 12, and consequently the strip to which the plate is secured, against the outer face of the door 5 and the inner face of the door frame 9.

In Figures 5, 6 and 7 side strips 16 and 17 have been shown applied to side edges of the upper and lower sashes 18, 19 of a window, a top strip 20 along the upper edge of the upper sash 18, 15 a bottom strip 21 along the lower edge of the lower sash 19, and an intermediate strip 22 along the top of the lower sash 19, all of said strips being similar to those previously described with exceptions presently noted. The side strips 16 and 17 are designed to bear against the sashes 18, 19, the strips 16 against the inner edges of the usual parting strip 23, as shown for instance in Figure 7, and the strips 17 against the inner edges of the inner stop strip 24. The top strip 20 is designed to fit against the bottom edge of the parting strip 23 and fit in between the side strips 18. The bottom strip 21 fits under the side strips 17 for the lower sash 19 and the intermediate strip 22 under the side strips 16 for the upper sash 18, and overlaps the bottom of the upper sash.

The side strips 16 for the top sash 18 are secured by hinges 25 to the inner trim 26 of the window to swing outwardly over said trim so as to be out of interfering relation to the lower sash 19 and permit the latter to be opened.

The top strip 20 is secured to the trim 26 by hinges 27, the bottom strip 21 to the spool cap 28 by hinges 29, and the intermediate strip 22 to the top of the lower sash 19 by hinges 30. The side strips 17 for the lower sash 19 are secured thereto by hinges 31 and are therefore adapted to be raised and lowered with said lower sash together with the intermediate strips 22.

45 All of the hinges 25, 27, 29, 30, 31 are similar to the hinges previously described with the exception that the movable plate, as shown at 32 in Figure 7, is right angular in the case of the hinges 25, 27 and 30 to facilitate fitting around the inner edge of the window frame 26. Also in the case of the hinges 25 there are preferably three on each side of the upper sash 18 vertically spaced apart and the intermediate hinge 25 on each side is provided on the movable plate 33 thereof with a forwardly extending post 34. A

strut rod 35 is secured at its ends to the movable plates 33 of the upper and lower hinges 25 on each side of the upper sash 18 and extended through the outer end of the post 34 of the intermediate hinge. This arrangement tensions the 5 movable plate 33 of the intermediate hinge 25 and prevents outward buckling of the related strip 16 away from the sash 18. Hooks, as at 36 are provided on the fixed plates of each intermediate hinge 25 to attach over the rods 35 and hold the 10 strips 16 in outwardly swung position when such position is desired.

The foregoing will, it is believed, suffice to impart a clear understanding of my invention without further explanation, since the use and application thereof have been set forth in connection with the description of parts.

Manifestly, the invention is susceptible of modification in other respects than as disclosed here-

in, and right is reserved to such other modifications as fall within the scope of the appended claim.

What I claim is:

5 The combination with a frame forming a rectangular opening, and a similarly shaped closure member fitting in said opening of transversely square weather strips covered with resilient material and extending along the top, bottom and side edges of said closure within said frame in flat engagement with one face of said closure and the inner face of said frame, and means urging said strips into tight engagement with said faces and comprising hinges upon which said strips are swingable from engagement with said faces to 10 obviate interference of the strips with said closure during opening of the same.

THOMAS MONROE HESTER.
